UNITED STATES PATENT OFFICE

WILLIAM E. WATTERS, OF MAYWOOD, ILLINOIS

AIR MASK

Application filed April 18, 1928. Serial No. 270,946.

The invention relates to improvements in air masks and more particularly to masks or shields for use by sand blast operators.

A principal object of the invention is to provide a mask having means for automatically keeping its windows clean while in use, to maintain a clear vision for the operator.

An object of the invention is to provide a mask with means for washing and filtering the inlet fresh air.

An object of the invention is to provide a mask with means for accelerating the exhausting of the foul air and keeping the exhaust port free from obstruction, to maintain its full area effective.

An object of the invention is to provide a mask adapted for use under a hood having a window, with means on the mask for keeping said window clean.

An object of the invention is to provide a mask with yielding means for engaging the face of the sand blaster, painter or other artisan.

An object of the invention is to provide a mask with an air supply line that will not hamper the free movement of the operator.

The objects of the invention are in general, to arrange the parts in such combination, as to form an efficient air mask adapted to be worn by a sand blast operator, under the usual hood. To provide means associated with the mask for maintaining the windows or eye-pieces of both shield and hood free from dirt and moisture, so that the vision of the wearer is not obstructed, and to provide means for washing the incoming air and accelerating the exhausting of the foul air and also to provide means for a snug comfortable engagement of the mask with the face, so arranged that free movement of the wearer is unhampered.

With the foregoing and such other objects in view as will appear as the description proceeds, the invention resides in the combination and arrangement of parts and in the details of construction hereinafter described and claimed, it being understood that changes in the precise embodiment herein described may be made within the scope of

what is claimed without departing from the spirit of the invention.

In the drawings:

Fig. 1 is a side elevational view of the improved mask shown attached to the face of a sand blast operator, the hood being indicated in broken lines.

Fig. 2 shows a front elevational view of the mask with the hood removed.

Fig. 3 is a view similar to Fig. 2, viewed from the opposite or inside of the mask.

Fig. 4 is an enlarged fragmental vertical central sectional view of the mask and hood taken along line 4-4 of Fig. 2.

Fig. 5 is a sectional view through the eye pieces or lens of the mask, taken on line 5-5 of Fig. 2.

As illustrated in the various figures of the drawings, the improved mask comprises a piece of flexible material 11, shaped to conform to the general contour of a human face, having openings adapted to receive transparent members to form windows 12 and an enlarged nose and mouth piece 13 arranged to carry an air filtering or washing element 19. Secured to the periphery of the mask, thus formed, is a cushion 16 which serves as an air seal in addition to a protector for the face of the wearer.

Fresh air is supplied to the inside of the mask through a substantially vertically disposed conduit 18, which preferably is secured to the outside of the mask. Connected to the upper end of this air conduit is a flexible conduit 25 which communicates with an air supply line located in the vicinity of the wearer. The air inlet conduit 18 has suitable openings in one side adapted to allow a sufficient amount of air to be discharged against the window 32 of the hood 31, usually worn over the mask as further protection.

The inlet conduit 18 is provided with a bypass extending through the mask and downwardly between the windows, which is provided with openings adjacent to the center of the windows to permit a small stream of air to be ejected upon the inner side of each of the windows to prevent moisture deposits.

Referring now to the drawings, a piece of flexible material 11, strong light leather be-

- ing preferable, is formed to conform to the general contour of a face and is provided with a pair of windows 12 mounted, in any suitable or approved manner near the upper 5 end thereof. Located on a vertical line running between the windows 12, and sufficiently distanced below the same, is an opening having secured to its edge a forwardly and downwardly extending tubular nose and 10 mouth piece 13 made of the same material as the face covering 11. This tubular extension or nose piece 13 has its forward end open and a cover plate or cap 14 securely closes the open end, and a series of annular 15 accordion pleats are provided to permit a limited amount of flexing.
- Secured around the edge of the face covering 11 is a sealing ring or cushion 16 which furnishes additional comfort and protection 20 to the forehead, cheeks and chin of the wearer, and is adapted to be inflated through a valve 17, provided on its lower side.
- The mask is held in place over the operator's face by adjustable straps 33 secured to 25 the mask and arranged to extend around and over the head, as shown in Fig. 1.
- To admit a plentiful supply of fresh air to the inside of the mask a rigid conduit 18 is secured to its outside, and extends downwardly between the window members 12. The lower end of this conduit 18 is bent outwardly at a point just above the mouth piece 12, and has its open end secured to and 30 communicating with said mouth piece at its extreme forward end. To afford protection to the wearer from the full force of the incoming air, through the conduit 18, which has normally a pressure of about 20 pounds, a fibrous porous substance 19, preferably a 35 sponge is inserted in the forward end of the mouth piece 13. This material 19 is preferably saturated with water to wash and insure a proper distribution of the air passing therethrough.
- 40 45 To prevent moisture from accumulating on the windows 12, an air conduit is provided in the form of a by-pass 21, which extends from the upper end of the rigid conduit 18 through the mask downwardly between the windows 12. The by-pass 21 is provided with 50 a pair of small ports 22 adjacent the central horizontal center line of the windows 12. These ports 22 are so positioned on the conduit that a stream of air is directed laterally 55 and angularly towards each window, thus the constant stream of fresh air passing over the surface of the window prevents moisture or dirt deposit thereon.
- The lower end of the by-pass 21 extends 60 into the mouth piece 13 and its open end is directed into a relatively large outlet or exhaust opening 23 provided on the upper side of said mouth piece. A fine mesh screen 24 (preferably 100 mesh) is mounted over the 65 outlet opening 23 to prevent unwarranted

entrance of sand particles or other foreign matter from the outside. This outlet opening is of sufficient diameter to exhaust all of the foul air discharged by the wearer, and its passage out is accelerated by the air from the by-pass 21.

70 A piece of flexible tubing 25 is connected to the upper end of the rigid conduit 18 and extends over and downwardly behind the head of the wearer to a belt 26, which is adapted to be adjusted about the waist of the operator and has a fitting 27 secured thereto, in this instance riveted, to which the tubing 25 is connected while the opposite end of the fitting 27 is adapted to be connected to an air supply tank or pump by flexible tubing 28.

75 By attaching the flexible tubing 25 to the waist, the wearer is allowed unhampered freedom of movement within the limits of said conduit.

80 It is customary to wear a hood 31, of the general combination shown in broken lines in Fig. 1, over this type of a mask to protect the uncovered parts of the wearer's head from flying particles of sand, etc. Said hood is provided with a plurality of window members 85 32 and is of sufficient length to extend to the shoulders of the wearer. Under ordinary working conditions, the windows 32 become covered on their inside with sand and moisture. To prevent this foreign matter from accumulating thereon, I propose to direct a spray of fresh air upon said window while the hood is in use in conjunction with the improved mask.

90 95 100 To attain this result a forwardly directed opening 34 is provided on the rigid conduit 18, adjacent the lens 12 of the mask. This opening is preferably in the form of a horizontally disposed slot to continuously direct a horizontal fan shaped spray of fresh air upon the inside surfaces of the windows 32, thus keeping them clear.

105 110 115 From the foregoing description it can readily be appreciated that a mask constructed in the above manner will afford ample protection to the face of the wearer, as well as maintain the vision of the wearer clear at all times, and finally the inflated cushion provided around the edge of the mask insures a tight fit and allows the operator to wear the mask over a considerable period of time without discomfort.

I claim:

- 120 125 130 1. A mask of the class described having, in combination, a face covering provided with an extending mouth piece having an exhaust opening, and being flexibly connected to said covering and arranged to carry an absorbent element, means for conducting fresh air through said absorbent element to the inside of the mask, a window in said covering, and a by-pass associated with said means having openings for discharging an air current against the inner side of the window to dry

any moisture deposit thereon, said by-pass exhausting in the exhaust opening and being arranged to aid in exhausting the air from the mask and in maintaining the effective area of the exhaust opening.

2. The combination of a mask comprising, a face covering, a window therein, means for conducting air to the inside of the mask and directing a current of said air outwardly away from said window and a by-pass on said means for directing a stream of air against the inside of the window, with a hood having a window, said hood enveloping the mask and arranged with its window in the path of said air current whereby said window is kept free from vision obstructing substances.

3. A mask of the class described, adapted to be inserted in a hood having a window, in combination, a face covering provided with an extending mouth piece, having an exhaust opening, flexibly connected to said covering and arranged to carry an absorbent element, a window in said covering, means for conducting fresh air through said absorbent element to the inside of the mask, auxiliary means associated with said means for discharging an air current against the inner side of the window of the mask to dry any moisture deposited thereon, said auxiliary means being arranged to aid in exhausting foul air from the mask and maintaining the full effective area of the exhaust opening, and an outlet being provided in the means for supplying fresh air, arranged to discharge a current of air outwardly onto the window in the hood to provide clear vision therethrough.

4. The combination with a mask comprising, a face covering having windows, a substantially rigid conduit on said covering arranged for conducting fresh air to the inside of the mask having an outwardly directed opening for directing a fan-shaped spray of fresh air away from said windows, a by-pass extending into said mask for directing a fresh air current against the inside of said windows to insure clear vision; with a hood having a window, said hood being arranged over the mask with its window in the path of the outwardly directed fresh air current whereby said window is maintained free from vision obstructing substances.

5. The combination of a mask comprising, a face covering having means for securing it to the head of a wearer, a window in said covering, means mounted on said covering for conducting fresh air to the inside of the mask and directing an auxiliary air current outwardly away from said window, and a by-pass in said means for directing a stream of air against the inside of said window, with a hood, said hood having a window and being arranged over said mask with said window in the path of said auxiliary air current whereby said window is kept free from vision obstructing substances.

6. A mask of the class described having, in combination, a face covering provided with a substantially tubular extending mouth piece having an exhaust opening and an accordion connection joining said mouth piece to said covering and an absorbent element in its end, a pair of windows in said mask above the mouth piece, a substantially rigid fresh air conduit extending downwardly on the outside of said covering between said windows having communication with the interior through said absorbent element, and a by-pass extending into said mask and downwardly between said windows having openings to permit a fresh air current to be directed against the windows to maintain clear vision, said by-pass terminating in said exhaust opening to aid the exhaust of foul air.

In testimony whereof I affix my signature at 10 South LaSalle Street, Chicago, Illinois.
